CLAIM

I claim the ornamental design for a tablet, as shown and described.

DESCRIPTION

FIG. 1 is a perspective view of a tablet.

FIG. 2 is a front view of the tablet illustrated in FIG. 1.

FIG. 3 is a back view of the tablet illustrated in FIG. 1.

FIG. 4 is a left elevation side view of the tablet illustrated in FIG. 1.

FIG. 5 is a right side elevation view of the tablet illustrated in FIG. 1.

FIG. 6 is a top plan view of the tablet illustrated in FIG. 1; and, FIG. 7 is a bottom plan view of the tablet illustrated in FIG. 1. The broken lines shown in the figures that are immediately adjacent to the shaded areas and define regions that are consistently unshaded, represent the bounds of the claim, while all other broken lines are directed to environment and are for illustrative purposes only; the broken lines form no part of the claimed design.
